Attn:*

UNITED STATES PATENT OFFICE.

BYWATER HUDSON, OF ST. PAUL, MINNESOTA.

DESIGN FOR A HERRING-BONE GRASS FLOOR-COVERING.

50.909.

Specification for Design.

Patented June 12, 1917.

Application filed March 31, 1916. Serial No. 88,177. Term of patent 14 years.

To all whom it may concern:

Be it known that I, BYWATER HUDSON, a citizen of the United States, residing at St. Paul, in the county of Ramsey and State of Minnesota, have invented a new, original, and ornamental Design for Herring-Bone Grass Floor-Coverings, of which the following is a specification, reference being had to the accompanying drawing, forming a part thereof, and wherein—

The figure is a view of a portion of the floor covering showing my new design.

I claim:

The ornamental design for herringbone grass floor covering, as shown.

BYWATER HUDSON.
